UNITED STATES PATENT OFFICE

159,261

GARMENT HANGER HOOK

John J. Fiechter, Willow Grove, Pa.

Application March 16, 1948, Serial No. 145,151

Term of patent 14 years

(Cl. D17—12)

To all whom it may concern:

Be it known that I, John J. Fiechter, a citizen of the United States, residing at Willow Grove, in the county of Montgomery and State of Pennsylvania, have invented a new, original, and ornamental Design for Garment Hanger Hook, of which the following is a specification, reference being had to the accompanying drawing forming part thereof.

Fig. 1 is a perspective view of a garment hanger hook, showing my new design, and

I claim:

The ornamental design for a garment hanger hook, substantially as shown.

JOHN J. FIECHTER.
